UNITED STATES PATENT OFFICE.

CLARENCE E. BARTLETT, OF ST. LOUIS, MISSOURI.

ATTACHMENT FOR JOURNAL BOXES.

Application filed June 29, 1925. Serial No. 40,180.

This invention relates generally to journal boxes of the type used on railroad rolling stock, and particularly to an attachment for a journal box which is so constructed and 5 arranged within said journal box that the theft of the brass associated with said journal box is rendered much more difficult than heretofore.

As is well known, journal boxes of the 10 type indicated above are each provided with a brass which is arranged adjacent to the journal within the journal box, said brass being provided with an inner face which is shaped to conform to the peripheral face 15 of the journal and being retained in its proper position by means of a wedge which is usually interposed between said brass and the top wall of the journal box. Prior to this invention it has been a rather easy task 20 for a thief to steal a brass, as it was only necessary for him to place a lifting jack beneath the journal box and raise said journal box a sufficient distance to permit the withdrawal of the brass, and because of the 25 ease with which the brasses could be removed the railroad operating companies suffered a very great financial loss each year because of the theft of a great number of brasses.

As an ordinary thing railroad yards and other places where railroad rolling stock is located are policed, so that for a thief to steal a brass without detection he must work rapidly and noiselessly. With the foregoing in mind, I have devised the attachment disclosed in the present application which, when associated with a journal box, will render it impossible for a thief to steal the brass thereof by jacking up said journal box 35 as heretofore. With my improved attachment in place in a journal box the only way in which the brass may be removed from said journal box by a thief would be for him to drive the hinge pin which holds the 40 lid of the journal box in place from its position and then remove both the lid and my improved attachment from the box. It is quite apparent that this would be a time-consuming and noise-producing operation 45 and if attempted would in most cases result in the discovery of the thief. My improved attachment is of extremely simple construction, and when arranged in a journal box will not in any way interfere with 50 the proper functioning of said journal box.

With the foregoing and other objects in

view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the 65 claims hereunto appended.

Fig. I is a vertical section through a journal box provided with my improved attachment, a portion of the axle associated with 70 said journal box being broken away.

Fig. II is a front elevation of the journal box illustrated in Fig. I, a portion of the lid of said journal box being broken away.

Fig. III is a horizontal section on line 75 III-III of Fig. I.

In the drawing, A designates a journal box of the ordinary type, said journal box comprising rear, bottom, top and side walls arranged to produce a housing B. The rear wall of the journal box illustrated in the drawing is provided with an opening C through which a journal D is extended, and the front wall of said journal box is provided with an opening E through which access may be had to the interior of the housing B, whereby the introduction of lubricant-bearing waste into the housing is provided for. By referring to Fig. I it will be seen that the journal box A is provided with a curved wall portion F at its lower forward 90 portion, and also that said box is provided with an inclined wall portion F' arranged adjacent to the opening E.

Extended upwardly from the top wall of the journal box A is a pair of ears G spaced 95 apart from each other in a horizontal direction, said ears being formed integral with said top wall of said box, as shown in Fig. I, and being each provided with an opening H formed therethrough. J designates the 100 lid of the journal box A, said lid being of the usual type and being provided with eyes K at its upper end which are arranged adjacent to the ears G so that a hinge pin L may be passed through the openings H 105 in the ears G and through the eyes K to hingedly secure said lid J to the journal box. M designates a leaf spring which is secured to the lid J and is adapted to cooperate with the faces on a lug N in a manner to retain 110 the lid J either in a closed position or in an open position. O designates a cover plate

which is mounted on the lid J in a manner to enclose the leaf spring and lug just referred to.

P designates the brass of the journal box 5 A, said brass having an inner face P^a shaped to correspond to the peripheral shape of the journal D and having an upturned portion P^b at its rearmost end. Q designates a wedge which is interposed between the brass 10 P and the lower face of the top wall of the housing B. Arranged within the housing B at the top thereof are lugs R which are adapted to prevent the easy removal of the wedge Q.

15 Thus far I have described a journal box of the common type which is found in use on railroads at the present time, and by referring to Fig. I of the drawing it is apparent that it would be a very simple matter 20 for a thief to extract the brass P from said journal box by merely raising the journal box by means of a lifting jack a sufficient distance to permit the brass and the wedge to be extracted. My improved attachment is 25 intended to prevent the removal of the brass in the manner described, and this attachment will now be set forth.

1 designates a plate provided at its top with a pair of extensions 2 which are shaped 30 to provide eyes 3 of the approximate size of the eyes associated with the lid J of the journal box. The lower portion of the plate 1 is provided with an opening 4, so that said lower portion of said plate is merely a rectangular strip, as shown in Fig. II. It will also be noted by referring to Fig. II that the opening 4 is narrower than the brass P, hence said brass may not be passed through the opening 4 in the plate 1 and through the 40 opening E in the journal box when said plate 1 is in place. Located at the upper end of the plate 1 is an integral band of material 5 which extends transversely of said plate, as shown in Fig. II. This band of material is longer than the width of the opening E at the front of the journal box, and as a consequence it overlaps the side margins of said opening and contacts with the outer face of the front wall of the box 50 adjacent to said opening. Secured to the transverse band of material 5 is a strip of material 6, said strip of material being of the same shape and dimensions as the band of material 5 and being secured to said band of material 5 by means of rivets or other fastening devices 7. The strip of material 6 is intended to add strength to the plate 1 at the point where it would probably be subjected to strain in the event an attempt were 60 made to extract the brass P from the journal box with the plate 1 in place.

To arrange my improved attachment in place in a journal box, the lid of the journal box is raised and the hinge pin L removed. 65 The lower end of the plate 1 is then intro-

duced into the interior of the journal box with the curved lower end portion 1' thereof, which has the same curvature as the inside face of the curved wall portion F of the journal box, in contact with said inside face of said wall portion F. The eyes 3 at the upper end of the plate 1 are then alined with the eyes K at the upper end of the lid J and with the openings H in the ears G on the top wall of the journal box. The hinge pin L is then passed through said registering eyes 3 and K and through said openings H in the ears G, whereby the lid J is hingedly fixed to the journal box and the plate 1 is rigidly fixed thereto. When the plate 1 is assembled as described, the opposite end portions of the transversely arranged band will contact with the outer face of the front wall of the journal box, whereby the lower end portion of said plate 1 is prevented from 75 swinging inwardly with the hinge pin as a pivot, and also because the lower end portion 1' of said plate 1 is in firm contact with the inner face of the wall portion F, said lower portion of said plate will be prevented from swinging outwardly. It is therefore plain 80 that the plate 1 is very rigidly interlocked with the journal box and held in a position which will prevent the removal of the members P, and because said plate is made of 85 relatively heavy material it would not be possible to force it out of the way without creating so much noise as to attract attention.

When an authorized person desires to remove a brass, for instance, to replace it with a new one, he may do so by removing the cotter pin L' from the hinge pin L and then removing said hinge pin, after which the lid J and plate 1 may be removed from the journal box. As stated in the preamble of this specification, a thief of course may also remove the lid and plate 1 as described, but as it would be necessary for him to make a great deal of noise in driving the hinge pin 105 out of place, he would in all probability be discovered.

By referring to Fig. II it will be noted that the opening 4 in the plate 1 is provided with a curved portion 8 at its upper end. The purpose of the opening 4 is to permit waste and lubricant to be introduced 115 into the housing B, and the purpose of the curved portion of said opening at its upper end is to permit inspection of the brass P by an authorized person.

I claim:

1. A journal box comprising a housing having an opening in a wall thereof through which access may be had to the interior of said housing, a lid adapted to close said opening, a hinge pin by means of which said lid is hingedly supported, a brass within said housing and arranged adjacent to a journal extended into said housing, and means whereby the easy removal of said 125

- brass is prevented, said means comprising a plate supported by said hinge pin and arranged adjacent to said opening, said plate having an eye at its upper end through which 5 said hinge pin passes and the lower portion of said plate being in contact with the inside face of said housing and an upper portion thereof being in contact with the outside face of said housing, said plate being so positioned as to prevent the passage of the brass through said opening.
2. A journal box comprising a housing having an opening in a wall thereof through which access may be had to the interior of 15 said housing, a lid adapted to close said opening, a brass arranged in said housing to contact with the journal, and means whereby easy removal of said brass is prevented, said means comprising a plate adapted to 20 prevent removal of the brass through said opening, said plate being interlocked with said housing to prevent displacement of the plate, and the interlocking means on said plate being partly inside of the housing to prevent outward displacement of the plate 25 and partly outside of said housing to prevent inward displacement of said plate.
3. A journal box comprising a housing having an opening in a wall thereof through which access may be had to the interior of 30 said housing, a lid adapted to close said opening, a hinge pin by means of which said lid is hingedly supported, a brass within said housing and arranged adjacent to a journal extended into said housing, and 35 means whereby the easy removal of said brass is prevented, said means comprising a plate supported by said hinge pin and arranged adjacent to said opening, said plate being interlocked with said housing and the 40 interlocking means on the plate being partly inside and partly outside of said housing to prevent displacement of said plate, and said plate being so positioned as to prevent the 45 passage of the brass through said opening.

In testimony that I claim the foregoing I hereunto affix my signature.

CLARENCE E. BARTLETT.
